DESCRIPTION

FIG. 1 is a perspective view of a first embodiment of a lavatory.

FIG. 2 is a front elevation view of the lavatory of FIG. 1.

FIG. 3 is a top plan view of the lavatory of FIG. 1.

FIG. 4 is a left-side elevation view of the lavatory of FIG. 1.

FIG. 5 is a right-side elevation view of the lavatory of FIG. 1.

FIG. 6 is a perspective view of a second embodiment of a lavatory.

FIG. 7 is a front elevation view of the lavatory of FIG. 2.

FIG. 8 is a top plan view of the lavatory of FIG. 2.

FIG. 9 is a left-side elevation view of the lavatory of FIG. 2; and,

FIG. 10 is a right-side elevation view of the lavatory of FIG. 2.

The broken lines immediately adjacent to the shaded areas represent the bounds of the claimed design while all other broken lines are for illustrative purposes only; the broken lines form no part of the claimed design.
